UNITED STATES PATENT OFFICE

RICHARD M. HORTVET, OF MINNEAPOLIS, MINNESOTA, ASSIGNOR TO MAHR MANUFACTURING COMPANY, OF MINNEAPOLIS, MINNESOTA, A CORPORATION

ROLLER HEARTH FURNACE

Application filed September 28, 1928. Serial No. 309,032.

My invention relates to roller hearth furnaces, and particularly to furnaces for heating rounded castings such as couplings. An object of the invention is to provide a device 5 of this character having a plurality of different sized rollers in the bottom thereof whereby castings of different sizes will be adequately supported and prevented from sagging while they are passing through the 10 furnace and are being heated therein. Another object is to provide a support for said rollers with provision for preventing the support from being buckled or misplaced by expansion and contraction tending to throw the 15 rollers out of their proper alignment. Another object is to provide means whereby the castings may be conveniently fed into and discharged from the furnace.

The full objects and advantages of my invention will appear in connection with the 20 detailed description thereof, and the novel features of my inventive idea will be particularly pointed out in the claims.

In the accompanying drawings which illustrate a practical embodiment of my invention,

Fig. 1 is a longitudinal vertical sectional view of the furnace. Fig. 2 is an enlarged fragmentary top plan view of the rollers 30 thereof. Fig. 3 is a view in transverse section on the line 3—3 of Fig. 5. Fig. 4 is a view in transverse section on the line 4—4 of Fig. 5. Fig. 5 is a fragmentary side elevational sectional view.

Referring to the construction shown in the drawings, the numeral 10 designates in general the walls of a furnace having suitably arranged openings 12 for the introduction of heat. The furnace is provided with a 40 heat resistant floor 14 in which a number of transverse metal I-beams 16 are embedded. The beams 16 have upturned flanges 18 to which one end of U-shaped metal members 20 are attached by cross rods 22 which pass 45 through the flanges thereof and through the flanges 18 as will be apparent from Fig. 4. The other ends of the U-shaped members 20 are not secured to the flanges 18 as will be understood from Fig. 5. From the latter 50 figure it will also be understood that the bot-

toms of the members 20 are offset upwardly at the ends to form portions 24 and 26 which fit over the upper flanges of the I-beams 16. The shoulders 28 and 30 of the end portions 24 and 26 are spaced from the sides of the 55 upper flanges of the beams 16 while the end portions 24 and 26 are spaced from each other. Since as previously explained the end portions 24 are not secured to the flanges 18 of the beams 16, it will be understood that ample provision is made for expansion and 60 contraction of the metal members which have been referred to. The upturned flanges of the members 20 provide bearings for a plurality of shafts 32 to which are secured pairs 65 of outer rollers 34 and pairs of inner rollers 36, the latter being considerably smaller than the rollers 34. In alternation with the shafts 32, the members 20 support a plurality of shafts 38 to which are secured pairs of rollers 40. It will be noted that the rollers 40 are not only intermediate in size between the 70 rollers 34 and 36 but each roller 40 is arranged between a large roller 34 and a small roller 36. The purpose of this arrangement 75 will be understood from Fig. 3 in which C, C', C² and C³ designate round or cylindrical castings which are progressively larger in size. From this figure, it will be observed 80 that different sized castings will be adequately supported by the rollers as the castings travel through the furnace. Adjacent the receiving end of the furnace, there are a number of reciprocating pushers 42 attached to the forward ends of arms 44, the other ends 85 of which are pivoted to the upper ends of swinging arms 46, the lower ends of which are pivoted to a fixed member 48. The outer ends of crank arms 50 are intermediately pivoted to the arms 46, the inner ends of these 90 crank arms being pivoted to a wheel 52 which may be driven from any suitable source of power. The castings to be heated are placed ahead of the pushers 42 which move them 95 through the furnace at the desired rate of speed dependent upon the speed of rotation of the wheel 52. At the discharge end of the furnace, there is an opening provided with a chute 54, the opening being normally closed 100 by a counterweighted door 56, which opens

when the castings slide down the chute. As will be seen in Fig. 2, the different sized rollers are close together in overlapping relation so that the stock which is being fed through the furnace is maintained in position without tipping.

I claim:

1. A roller hearth furnace comprising an enclosing structure, a plurality of shafts in the bottom thereof, a pair of large outer rollers and a pair of small inner rollers mounted on alternate ones of said shafts, and a pair of intermediate sized rollers mounted on each of the intervening ones of said shafts, each of said intermediate sized rollers being arranged between one of said large rollers and one of said small rollers.
2. A roller hearth furnace comprising an enclosing structure having a refractory bottom, a plurality of transverse metal beams embedded in said refractory bottom, a plurality of longitudinal metal supporting members extending between said beams respectively, the ends of said members being spaced from each other with one end of each member attached to the adjacent one of said beams and the other end supported for free movement, and a plurality of rollers carried by said supporting members.
3. A roller hearth furnace comprising an enclosing structure having a refractory bottom, a plurality of transverse metal I-beams embedded in said refractory bottom, a plurality of longitudinal metal supporting members extending between said beams respectively with their ends offset to overlap the beams, said ends being spaced from each other with one end of each member attached to the adjacent one of said beams and the other end supported for free movement, and a plurality of rollers carried by said supporting members.

In testimony whereof I hereunto affix my signature.

RICHARD M. HORTVET.
